UNITED STATES PATENT OFFICE

P. AUGUSTE VUILLE, OF CHAUX DE FONDS, SWITZERLAND.

STEM WINDING AND SETTING ATTACHMENT FOR WATCHES.

SPECIFICATION forming part of Letters Patent No. 225,542, dated March 16, 1880.

Application filed December 24, 1879.

To all whom it may concern:

Be it known that I, P. AUGUSTE VUILLE, of Chaux de Fonds, Republic of Switzerland, have invented a new and useful Improvement 5 in Watches, which improvement is fully set forth in the following specification.

This invention relates more particularly to that class of watches known as "stem-winding." The principal advantages obtained 10 thereby are found in the fewness of parts, the simplicity, compactness, and solidity of the mounting and movement, and the means of securing the movement in the case, and the capacity for ready repair, inasmuch as all the 15 parts can be readily supplied by any watchmaker.

The invention comprises improvement in the construction of the mounting for the movement; in the main plate and combination of 20 parts therewith; in the mechanism for winding the watch, and setting the hands, composed of a tilting lever with suitable wheels arranged on the face of the main plate, that is just beneath the dial; in the special construction of this mechanism, and in the construction of the push-pin for placing said mechanism in gear for setting the hands, all as hereinafter more fully set forth.

It is unnecessary here to describe the several kinds of watches heretofore manufactured, 30 as my present invention and its advantages, as above stated, will be readily perceived and appreciated by those skilled in the art without such description. With regard, however, 35 to the mechanism for winding the watch and setting the hands, I would say that while a tilting lever carrying these gears has been used, so far as I am aware, it has always been located back of the main plate, and the parts 40 are also differently constructed.

In order that the invention and the manner of carrying the same into effect may more clearly appear, reference is made to the accompanying drawings, which form a part of this 45 specification, and in which—

Figure 1 is a front view of the improved watch with dial removed; and Figs. 2 and 3, a back and detail view, respectively.

The same letters indicate like parts where 50 they occur.

A main plate, A, and a three-quarter top

plate, B, secured together by screws *a'*, inclose between them the greater part of the train, the escapement and balance-wheel being supported by bridges attached to the main plate. 55 The opposing faces of the two plates are recessed to receive the wheels of the train, which have bearings in said plates. The number of the wheels in the train and the escapement are such as are common in watches, and need 60 no description. The escapement shown is known as "cylinder-escapement;" but other forms, as the anchor-escapement, could be used, an additional supporting-bridge being required for the latter. 65

The face of the main plate, which lies just below the dial, (see Fig. 1,) is recessed to receive the wheels 1 2 3 4, which impart motion from the central arbor to the hour-hand.

From the back a circular opening is made 70 to contain the barrel 5; but a portion, *a*, is left on the face to form a bridge for support for the arbor thereof. The barrel-bridge is thus formed out of the thickness of the main plate. Below this bridge *a* is the winding-wheel 6, 75 which is in the same plane with the wheel 2. Near the periphery of the main plate is a circular groove, *b*, which is formed circular for convenience in turning. Its depth is sufficient to receive the fixed ends of the spring *c* and 80 click *d*, so that they are flush with the upper surface of the main plate. The spring and click have their fixed ends conformed to the shape of this groove, and are held by means of a single screw each. The click or spring- 85 pawl, formed of a single piece of metal, engages with the teeth on the winding-wheel 6, and allows it to turn in one direction only.

Three wheels, *e f g*, are held in position in a recess in the main plate by means of the lever 90 *h* and a single screw, *i*. The latter screws into a cylindrical projection on the face-plate. The three wheels *e f g* fit over cylindrical projections from the back of the lever *h*, formed in one piece therewith, and mesh with each 95 other. They are in the same plane as the wheels 2 and 6.

The projection upon which the wheel *f* turns is hollow and encircles the projection from the main plate above mentioned. The construction is clearly shown in Fig. 3.

From the side of the main and three-quar-

forming the mounting for the movement. The winding-arbor, *k*, projects. At the top it is squared, and at the lower end carries a wheel 7, which engages with the wheel *f*. The lever *h* at one end is grooved on the face side to leave a projection, *h'*, against which the free end of the spring *c* rests. Below this end of the lever a narrow and deep recess, *l*, is formed through the main plate to the three-quarter plate, into which recess is an opening from the side. A pin extends from the back of the projection *h'* into said recess.

The casing *C* is formed with a middle ring, in the usual way, and a pendant, *D*, at one side. In this pendant is a central opening, through which the key-pipe *m*, attached to the crown-piece *m'*, extends, and in which it is free to turn. The crown-piece and key-pipe are held in position by a screw or pin on the pendant, which projects into an annular groove in the outside of the key-pipe.

At the side of the pendant, Fig. 1, is an opening, through which the push-pin *n* projects. This push-pin is formed of a single piece of metal wire, with projections *n'* formed integral therewith, by forcing up or turning off the metal. These projections *n'* limit the movement outward of the pin. In order to secure the movement in the case the crown-piece and key-pipe are removed. The winding-arbor is inserted in the hole in the pendant, and the inner end of the pin *n* is made to project into the recess *l*. The crown-piece and key-pipe are then secured in position, with the squared end of the winding-arbor within the key-pipe, which is squared also, the screw *o* is turned, and the movement is solidly connected with the case. There is, of course, the usual rim on the periphery of the main plate. The push-pin *n* rests against the pin at the back of the projection *h'*, and when depressed oscillates the lever *h*. When released the spring *c* returns it.

At *p*, Fig. 1, are two holes, in which the pins attached to the back of the dial-plate are placed to secure the latter in position.

At *q r* are shown plates which fit in recesses in the main plate, and of which *q* is small and of brass, and holds one of the jewels of the balance-wheel arbor, and *r* aids in retaining this plate in position, and to it the bridge supporting the opposite end of the balance-arbor is secured by two small pins and a screw.

The movement can be placed in a case of any kind, of the proper size, as the crown-piece and key-pipe form a part of the case and not of the movement.

The operation of winding the watch is effected by turning the crown-piece so as to rotate the winding-wheel in the proper direction. By pushing upon the pin *n* the lever *h* is tilted, so that the wheel *g* engages with the wheel 2. The hands can then be set by turning the crown-piece.

When the lever is in its normal position,

if the crown-piece be rotated in a direction opposite to that for winding the watch, the effect is simply to tilt the lever *h* slightly as each tooth passes.

Having thus fully described my said invention, and the manner in which the same is or may be carried into effect, what I claim, and desire to secure by Letters Patent, is—

1. In a stem-winding watch, the winding-arbor held between the main and three-quarter plates, which inclose and carry also the train of the watch, substantially as described. 75

2. The barrel-bridge, formed in one piece with the main plate, in combination with the barrel-arbor, supported thereby, and the winding-wheel, turning on said arbor under the bridge and exposed at one side, substantially as described. 80

3. The combination, with the main plate and barrel-bridge, formed in one piece therewith, of the winding-wheel turning beneath said bridge, and the click, formed of a single piece of steel, let into the face of the main plate and engaging at its free end with the teeth of the winding-wheel, substantially as 85 described. 90

4. The main plate, formed with a circular groove on the face near its circumference, and having the click for the winding-wheel and the spring connected with the hand-setting mechanism, attached thereto by their fixed ends, conformed to and secured in said groove, substantially as described. 95

5. The combination, with the winding-wheel and the wheels for imparting movement to the hour-hand, arranged upon the face of the main plate below its surface, of the tilting lever, also arranged on the face of the main plate, and carrying a wheel at each end, the said wheels engaging at all times with a centrally-arranged wheel, and adapted to be brought into gear, one or the other, with the winding-wheel or with one of the hour-hand wheels through the tilting of said lever, substantially as described. 105

6. The tilting lever, in combination with the three wheels turning on projections at the back of said lever, the main plate with a projection on its face, and a single screw retaining the lever and its wheels in position on the 110 main plate, substantially as described. 115

7. The push-pin having projections upon its surface, with one end resting against the tilting lever which carries the three gears and the other projecting through the center 120 ring of the case, the movement outward of said pin being prevented by the aforesaid projections, substantially as described.

In testimony whereof I have signed this specification in the presence of two subscribing witnesses. 125

P. AUGUSTE VUILLE.
